Patented Dec. 5, 1967

209,460

BALL TOY

Robert K. Ostrander, Jr., East Aurora, N.Y., assignor to
Fisher-Price Toys, Inc., East Aurora, N.Y., a corpora-
tion of New York

Filed Feb. 28, 1967, Ser. No. 5,979

Term of patent 14 years

(Cl. D34—15)

FIG. 1.

FIG. 2.

FIG. 3.

FIG. 4.

FIG. 1 is a front elevational view of a ball toy showing my new design;

FIG. 2 is a side elevation thereof as viewed from the left in FIG. 1;

FIG. 3 is a side elevation thereof as viewed from the right in FIG. 1, and

FIG. 4 is a top plan view thereof.

I claim:

The ornamental design for a ball toy, substantially as shown.
